J. HAMILTON

HOISTING TRUCK

Filed Sept. 27, 1922

UNITED STATES PATENT OFFICE.

JAMES HAMILTON, OF WASHINGTON, DISTRICT OF COLUMBIA.

HOISTING TRUCK.

Application filed September 27, 1922. Serial No. 590,838.

To all whom it may concern:

Be it known that I, JAMES HAMILTON, a citizen of the United States of America, and a resident of the city of Washington, in the 5 District of Columbia, have invented certain new and useful Improvements in Hoisting Trucks, of which the following is a specification, reference being had to the accompanying drawings.

10 This invention relates to improvements in hoisting-trucks and particularly to improvements in hoisting-trucks of the general type disclosed in United States Patent No. 1,176,684, issued March 21, 1916, in which 15 the rack-actuating pinion operated by a handle-controlled bar is, by reason of the rack's being provided with ringlike teeth, maintained in mesh with the rack throughout a wide range of horizontal swing or dis- 20 placement of the truck-handle. An object of this invention is to provide a truck of the type just mentioned which will be simple in construction, comparatively cheap in manufacture, and practicable, durable and 25 efficient in operation and use. Other features of this invention will be brought out hereinafter, as the description of the truck in which the same is embodied progresses.

In the drawings illustrating the principle 30 of this invention and the best mode now known to me of applying that principle, Fig. 1 is a vertical section on the line 1—1, of Fig. 2, so much of the hoisting-truck being illustrated as is necessary for the pur- 35 pose in hand; and Fig. 2 is a plan view of the parts shown in Fig. 1, the handle being shown in section.

The platform *b* (sometimes called the lift- 40 ing-platform) is mounted on the truck-frame *a* in such a manner that it is capable of being swung up from and down towards the truck-frame *a*; and, for this purpose, each of the four corners of the platform *b* is connected with the truck-frame *a* by means of 45 a link *c*, a type of connection that is old in this art. Although the truck-frame *a* is not shown as provided with rear-wheels, it will be understood that the truck-frame *a* is so supported. The platform *b* carries, at its 50 front end, a transverse-shaft *d*, to which is pivotally connected the upper end of the link *c*, of which the lower end is pivotally joined to a side-bar *a''* of the truck-frame *a*. The structure so far described is old

(see, for example, the Forbes United States 55 Patent, No. 368,883, granted August 23, 1887), generically considered.

The truck-frame *a* is provided with a front cross-beam *a'* to which are rigidly fastened the lower ends *e''* of a pair of standards *e*, the upper ends of which approach each other and carry an annular seat or collar *f* in which is firmly fastened (as by means of the pin *g*) the upper end of a guide-post *h*. The standards *e* constitute a 60 yoke in which the position of the guide-post *h* is fixed. On the guide-post *h*, there is mounted, free to slide up and down, a hollow, sleeve-like member *i* that is sometimes called a "spool." The front face of 65 this slidable sleeve *i* is formed with a rack *j* comprising a vertical series of teeth *j'* that are of the same ringlike type as are the teeth of the slidable sleeve shown and de- 70 scribed in the Weusthoff United States Patent No. 92,678, July 13, 1869; but the teeth *j'* are mutilated and do not go around the sleeve *i* completely to form full circles or rings. The sleeve *i* may be connected with 75 the front end of the lifting-platform *b* in 80 any suitable way. In the particular embodiment illustrated in the drawings, the old form of link connection is shown, wherein a lift-link *k* is provided, the upper end *k'* of the lift-link being pivotally connected to the rear 85 face of the sleeve *i*, while its lower end *k''* is pivotally connected with the transverse shaft *d* that is carried by the front end of the platform *b*. The guide-post *h* is formed 90 with vertical guide-grooves *h'*, with the walls of which engage guide-ribs *i'* formed upon and projecting inwardly from the wall of the centrally-located passage of the toothed spool *i*. In the front cross-beam *a'* of the truck-frame *a*, there is formed an opening 95 *a'*, in which there is seated, free to oscillate about its vertical axis, a carrier *m* formed with a pair of upwardly-extending arms *m'* that carry a pivot-pin *m''* upon which is fulcrumed a lift-lever *n*. The inner end of the latter is formed with a toothed segment *n'*, the teeth *n''* of which lie in a vertical plane and are arranged to engage the teeth *j'* of the rack *j*, so that, when the lift-lever *n* is swung on its fulcrum *m''*, the slidable sleeve or spool *i* will be raised or lowered, and the platform *b* will be lifted or allowed 100 to drop back upon the truck-frame *a*. The 105

outer end of the lift-lever n is formed with a notch n' with the wall of which a lug o' formed on the handle-bar o is adapted and designed to engage, so that the handle-bar o may, by such engagement, be interlocked with the lift-lever n . The inner end of the handle-bar o is bifurcated and the forks or branches o'' are formed with slots o'' , through which and a hole in the outer end 10 of the lift-lever n there passes a pivot-pin p . The slots o'' permit the handle-bar o to be pulled outwardly so as to disengage it from the lift-lever n . The lower end m' of the carrier m projects below the cross-beam a'' and enters a recess q'' formed in the top 15 of a caster-wheel mounting q that carries a shaft q' upon the ends of which are mounted the wheels r . A pin q'' serves to fasten the caster-wheel mounting q to the lower end m' of the lift-lever carrier m . Pivotally mounted on the top of the cross-beam a'' of the truck-frame a , there is a foot-operated latch s the inner or rear end of which is formed with a tooth s' adapted and designed to engage a tooth s'' formed upon the platform b , when the same has been raised, whereby the platform b may be locked in its lifted position. The latch or dog s may be tripped by the operator's placing 20 his foot on the pedal s'' , whereby the teeth s', s'' , are disengaged from each other and the platform b is allowed to sink back upon the truck-frame a . The lift-lever mounting m is formed, in its top, with a socket or recess h'' into which projects the lower end of the guide-post h , whereby 25 solidity of structure is ensured.

When the handle-bar o is interlocked (see Fig. 1) with the lift-lever n through the engagement of the lug o' with the wall of the notch n' , and is thrown downwardly into its dotted line position in Fig. 1, the lift-lever n will be swung on its fulcrum-pin m'' and the toothed segment n' will take the position indicated by dotted lines and will lift the spool or toothed sleeve i , which will slide upwardly along the fixed guide-post h . This upward movement of the sleeve i is, through the lift-link k , transmitted to the platform b , which will now swing upwardly from the truck-frame a and will, at the end of its upward travel, be locked in its raised position by the engagement of the tooth s' of the locking dog s with the tooth s'' formed 40 on the front end of the platform b . The raised position of the latter and its actuating mechanism is indicated by dotted lines in Fig. 1. The platform b remains, in its raised position, connected with the truck-frame a through the intermediary of the links c , of which there are four but only one of which is shown, as has been hereinbefore explained. Giving to the teeth of a rack an annular or ringlike shape is a common expedient old in the mechanic arts and is adopt-

ed when it is desired to maintain the rack and its actuating pinion in mesh each with the other, despite the relative displacement of either of these interengaging members in a plane at right-angles to the path of travel of the rack, when the pinion is turned to drive the rack. In the present instance, the provision of the rack j with ringlike teeth j' permits the segment n' to remain in mesh with the rack j , as the handle-bar o is swung from side to side of the truck-frame a , and the truck is steered in pulling it from place to place, whereby the slideable sleeve i may be raised and the platform b may be elevated irrespective of the fact that the handle-bar o 75 may not occupy a particular position (e. g., pointing straight to the front of the truck). 80

In accordance with the provisions of the patent statutes, I have herein described and shown the embodiment of this invention that is preferred by me; but I desire it to be distinctly understood that I fully realize that changes may be made in the structure herein and hereby disclosed, and that I intend to include within the scope of the 85 claims that follow hereinafter all modifications of the preferred form of this invention that do not depart substantially from the spirit thereof.

I claim:

1. A hoisting-truck including a truck-frame; a platform arranged thereabove for movement therefrom and theretowards; a stationary guide-post fixed in position upon the truck-frame; a sleeve connected with the platform and slideable up and down along the guide-post and provided with a rack having ringlike teeth arranged one above the other; a toothed member which engages the rack and by which the sleeve is caused to travel along the stationary guide-post; and a carrier in which the toothed member is mounted and which is rotatably mounted in the truck-frame and which carries the toothed member in its movement from side to side thereof while the teeth of the toothed member remain in operative mesh with the ringlike teeth of the rack.

2. A hoisting-truck including a truck-frame; a platform arranged thereabove for movement therefrom and theretowards; a stationary guide-post fixed in position upon the truck-frame; a sleeve connected with the platform and slideable up and down along the guide-post and provided with a rack having ringlike teeth arranged one above the other; a toothed member which engages the rack and by which the sleeve is caused to travel along the stationary guide-post; a carrier in which the toothed member is mounted and which is rotatably mounted in the truck-frame and which carries the toothed member in its movement from side to side thereof while the teeth of the toothed member remain in operative mesh with the ringlike teeth of the rack.

ringlike teeth of the rack; and a steering-wheel the direction of travel of which is controlled by the position of the carrier.

3. A hoisting-truck including a truck-frame; a platform arranged thereabove for movement therefrom and theretowards; a stationary guide-post fixed in position upon the truck-frame; a sleeve connected with the platform and slideable up and down along the guide-post and provided with a rack having ringlike teeth arranged one above the other; a toothed member which engages the rack and by which the sleeve is caused to travel along the stationary guide-post; a carrier in which the toothed member

is mounted and which is rotatably mounted in the truck-frame and which carries the toothed member in its movement from side to side thereof while the teeth of the toothed member remain in operative mesh with the ringlike teeth of the rack, the carrier being formed in its top with a recess into which the lower end of the guide-post projects; and a steering-wheel the direction of travel of which is controlled by the position of the carrier. 20 25

Signed at the city of Washington, in the District of Columbia, this twenty-sixth day of September, 1922.

JAMES HAMILTON
